UNITED STATES PATENT OFFICE.

NICHOLAS W. PARK, OF PROVIDENCE, RHODE ISLAND, ASSIGNOR, BY MESNE ASSIGNMENTS, TO PROCTOR & SCHWARTZ, INC., OF PHILADELPHIA, PENNSYLVANIA, A CORPORATION OF PENNSYLVANIA.

DRIER.

Application filed April 1, 1921. Serial No. 457,666.

This invention relates to improvements in driers. More particularly it relates to air driers for material in a finely divided state, such as pigments, chemicals and the like, although it will be evident that it can be used for withdrawing moisture by evaporation generally. It is illustrated as it may be applied in apparatus adapted to hold the material in trays, the principle being to 5 arrange the trays in a stack and to force heated air horizontally therethrough, passing it over the exposed material in the trays. Apparatus of this general type has been in use for many years in various forms. It is 10 an object of the present invention to provide improvements in the direction of increasing the speed and perfecting the uniformity of the evaporating effect. It is also an object to provide the desired high efficiency at a 15 low figure for first cost and for operation, and with great simplicity of elements and arrangement. It is a further object to arrange for the automatic shifting of the controls by which the moisture absorbing quality 20 of the air is maintained at desired degree, thereby limiting the consumption of steam or other heating agent and varying it according to the varying needs at different 25 stages of the drying. It is another object to produce a uniformity of effect wherever the material may happen to be located in the 30 various trays. This is a matter of considerable importance because for satisfactory results it is necessary to run the machinery until the whole of each batch is dried to the 35 required degree. If there be a quantity of the moist material which dries more slowly about the region opposite the axis of the fan, as I have found in certain machinery tested, 40 or if the material which is sheltered from draft of air because it is next the edge of the tray, remains moist longer than that in the middle, there is waste of power and a marked reduction in the capacity of the 45 whole apparatus measured in quantity of output per unit of time.

In the apparatus illustrated in the accompanying drawings, which show one embodiment of the invention, I have found that the 50 objects can be attained by the simple means of constructing an element producing distributive retardation of the air which has passed the trays where the drying is done and is flowing to the fan. In practice I

have found that a reduction of 10 per cent 55 of the area of the passage, making a vacuum of about one inch of water pressure in the space immediately adjoining the rotating fan, as compared with the space where the trays are, is sufficient to produce the desired 60 result, it being understood that the 10 per cent reduction is distributed with approximate uniformity over the entire cross section of flow at this place. This makes such an equal distribution of the current flow 65 through all parts of the adjacent section of the stack where the air is performing its drying function upon the material, that the difference in pressure is hardly observable as between the central and the top or bottom 70 trays of the stack. Moreover by setting this retarding element at a little distance from the edge of the stack of trays, for which in practice I find 4 to 6 inches suitable, the nearer edges of the trays are in the stiller 75 portion of the air, so that the drying proceeds with uniformity in all parts of each tray, down from the surface to the bottom of each tray load, both at the middle and close to the edges thereof. The openings 80 through the retarding element provide uniform pull on air, from top to bottom of the adjacent stack section, notwithstanding that the pull of the fan itself on air from top to bottom is not at all uniform. This is because of the equalizing effect of the vacuum chamber constituted between it and the fan. The invention may be applied in various 85 forms; and it is intended that the patent shall cover by suitable expression in the appended claims, whatever features of patentable novelty exist in the invention disclosed. 90

In the accompanying drawings:

Figure 1 is a front elevation in section, of 95 a complete drier; and

Figure 2 is a side elevation of the same in section on the line 2-2 of Figure 1.

Referring to the drawings, 10 indicates the whole, comprising top, bottom and four sides, of an enclosure which is illustrated as having an entrance opening 11 and a discharge opening 12 for air and containing a fan 13, driven by any suitable means such as a pulley, for drawing air from the inlet 11 toward the discharge opening 12. In practice these openings will be more or less closed respectively by the pivoted shutters 11' and 12' so that the greater part of 100 105 110

the air moved by the fan is merely circulated within the enclosure. To this end the enclosure is divided on a horizontal plane about midway of its height by a partition 14 which 5 extends from front to back through the middle but stops short of each side or end so that air driven by the fan can there pass from the upper to the lower section at one end and from the lower to the upper section at the 10 other end thus circulating around the horizontal partition 14. In the middle portion of the inclosure above and below the partitions, are racks 15 which may contain trays 15, some of which are shown in position, to 15 hold the material which is to be dried. The racks for holding these trays are open-work affairs permitting the air to pass freely through them, although the passage is, of course, somewhat obstructed by the upright 20 portions of the rack, if the same is made of angle iron as illustrated, or by the side wall of every tray which is in position. In each end section is a coil 18 of steam piping in any suitable arrangement for heating the 25 circulating air and reheating it according to well known practice.

A principal feature of the invention consists in the provision of the retarding plate 20. In the arrangement illustrated in the 30 drawing the fan is at one end in the upper section and is arranged to draw the air away from the stack of trays in that section. A partition is provided around the perimeter of the fan to centralize the 35 flow of air therethrough and to prevent any retrograde movement thereof past the fan. The retarding plate is a foraminous partition placed entirely across the upper section at a location between the ends of the 40 trays and the fan, whereby the area of the passage is reduced a predetermined amount, for which ten per cent has been found satisfactory. Its function is to restrict the 45 flow of air to the entrance side of the fan so that the volume of air passing through the plate is less than the capacity of the fan. By thus limiting the quantity of air entering the chamber 22, located between the plate and the fan an observable degree of vacuum 50 is created therein, which causes the pressure of the air in this chamber to be less than the pressure of the air on the tray side of the plate. As the rapidly moving end portions of the fan blades do not get a free and full 55 supply of air from the edge portions of the foraminous partition, they draw from the middle portion thereof, and make a uniform distribution of draft; and since this difference in pressure is approximately the same 60 at every opening in the plate, the flow of air from the tray side thereof will be at uniform velocity throughout the entire upper section of the enclosure. After being drawn through the fan, a large portion of the air is deflected 65 downward past the end of the horizontal

partition 14 into the lower section of the drier. There it comes into contact with a coil of steam pipes which heat it and thereby increase its moisture absorbing capacity as it flows around them, after which it 70 passes through the framework of the rack, and on over and between the loaded trays of the bottom section, taking up moisture from the material placed thereon to be dried. It continues through the rack at the other 75 end of the trays beyond which its course is again altered so that it moves upward through another heated coil of pipes, which perform the same function as the coil first encountered, and then horizontally again 80 along through the top section between the trays to the retarding plate, thus completing the cycle of movement.

Inasmuch as the action of the drier is very rapid the air in its repeated circulation of the enclosure soon would diminish in drying power. This is readily avoided by the arrangement of the openings 11 and 12, which are so placed that a proportion of the air approaching the upper stack is drawn 85 from outside fresh air, and a proportion of the air which leaves the fan goes outside, instead of continuing in circulation. The necessity for changing the air diminishes as the moisture of the material in the trays become less; and it is therefore possible to arrange for the openings 11 and 12 to be gradually closed during a drying operation. A clock 24 or other suitable mechanism, having a revolving drum 26 is provided for 90 winding up cables 27 and 28 which are fastened to the shutters 11' and 12' respectively, and which upon being wound on the drum cause these shutters to gradually close 95 the openings 11 and 12. The shutters may be adjusted from time to time by hand, or may be operated and controlled by clock work. On standard work, when rate of 100 progress can be forecast, such a clock may be started at the start of the run and may 105 be arranged, for example, so that there is a cam or other rate varying device (not shown) whose rotation by the clock controls the position of the shutters. Assuming that the material has 50 per cent of 110 moisture at the start, and it will be suitable treatment, the cam may be so designed that for the first hour the openings of the shutters will remain at whatever stage they 115 were set by the operator, and that thereafter the clock and cam gradually will close the openings until, say at the end of the 6th hour, only 10 per cent of the original moisture being then left, the shutters are then 120 closed and the run is completed in another 125 two hours with the shutters closed.

During operation the retarding plate acts as an equalizer for the flow through the stack, the flow of the same air being unequal 130 through the immediately adjacent fan. It

acts somewhat like a dam having a wasteway extending entirely across a stream of water, in that it produces a body of air which is moving uniformly to the plate, and which bears somewhat the same relation to the air which has passed the plate as the still water in a reservoir does to the stream which issues from it. It is not necessary that this equalized air move at a high rate of speed, but its speed will depend more or less on the degree to which the retarding element obstructs the passage. As that fraction of the air which is about to pass through the plate acquires higher velocity, it is desirable to put the retarding plate at a little distance from the stack, leaving the space 30 for which in practice 4 inches has been found sufficient, so that the nearer edge of each tray is within the zone of stiller air equally with other parts of the tray. Under these circumstances the drying proceeds with uniformity in all parts of each tray. A slight difference of pressure is sufficient to produce this result.

Apparatus such as that described has been discovered by experiment to give an improvement in efficiency, resulting in a considerable saving of power, as measured in the amount of steam consumed, in heating and in power, per pound of water evaporated. The marked improvement which it has shown over other types that I have known, with a close approach toward the theoretically possible minimum of steam required per pound of water evaporated, I consider to be due to the fact that the equalizing of the drying avoids the waste found in other apparatus, where the operation of machinery has to be continued long after some parts are dry, and to the fact that it can be controlled so that only the amount of fresh air actually needed to prevent too great rise of humidity is introduced, thus saving in the amount of heating needed.

I claim:

1. A drying apparatus comprising in combination a rectangular enclosure, having one end open for free ingress of a drying agent, adapted to contain, throughout substantially the whole of its cross-sectional area, moist material to be dried; means approximately filling the outlet end of the enclosure, adapted to exert a direct suction at substantially all parts of the cross-sectional area of the outlet, for drawing a gaseous drying agent through the enclosure past the moist material; and means, interposed between the last

said means and the material and extending throughout the cross-sectional area of the enclosure, adapted to equalize the velocity of the drying agent throughout the said cross sectional area.

2. A drying apparatus comprising in combination a rectangular enclosure, having one end open for free ingress of a drying agent, adapted to contain, throughout substantially the whole of its cross-sectional area, moist material to be dried arranged in separated containers, means, approximately filling the outlet end of the enclosure, adapted to exert a direct suction at substantially all parts of the cross-sectional area of the outlet, for drawing a gaseous drying agent through the enclosure; and a retarding plate equal in size to the outlet of the enclosure inserted across the path of the drying agent, whereby velocity is equalized in that portion of the agent which is held back; the said plate being spaced at a distance from the suction means and at a little distance in the direction of flow beyond said containers, sufficient for the containers to be outside of the zone of increased velocity of the agent which is about to pass through the plate.

3. A drying apparatus comprising in combination an enclosure having a rectangular passage therein with one end open for free ingress of air; containers arranged substantially throughout the cross-sectional area of said passage for holding material to be dried; a fan almost filling the outlet end of the passage adapted to exert direct suction at substantially all parts of the cross-sectional area of the passage, arranged with its line of draft of air extending through and parallel to the said passage having the containers; and means interposed between, and spaced at a distance from, the fan and the containers, comprising a foraminous plate having impervious portions distributed with approximate uniformity across the passage, between a multiplicity of small openings, whereby the flow of air to the fan is restricted to less than its capacity, and a partial vacuum is created in the passage between it and the plate, said vacuum and plate causing equalization of draft of air through all parts of said plate.

Signed at Providence, county of Providence, and State of Rhode Island, this twenty-sixth day of March, 1921.
